CUTTER BLADE LOCK

Ralph R. Weddell, Shelton, Conn., assignor to
 The O. K. Tool Company, Inc., New York, N. Y.,
 a corporation of New York

Application April 30, 1931, Serial No. 534,048

9 Claims. (Cl. 29—105)

This invention relates to cutting tools and is more particularly concerned with cutters of the inserted blade type.

It has for its primary object to provide a cutter with insertable or replaceable blades in a manner such that the tool when assembled will be exceedingly rigid and durable and capable of withstanding the excessive stresses of high speed present day tooling operations.

10 A further object of this invention is to provide an improved fastening means for the blades to insure of their being locked rigidly within the tool head along the entire faces of the portions thereof that do not project from the cutter body, 5 and as an additional refinement, to arrange the locking devices so that tooling stresses are transmitted directly to the cutter body and tend more firmly to seat the blades in the holder.

Still another concept of this invention is to 20 minimize the amount of grinding of the blades necessary in resharpening by constructing the blade lock in a manner necessitating but a single adjustment to effect simultaneously a repositioning of the blade in two directions, as for example, 25 radially and axially in the case of a face mill, slotting cutter, etc.

In carrying out the objects in accordance with this invention it is proposed to construct the cutter body of a suitable grade of strong tough 30 material and provide at its outer end or periphery thereof, as the case may be, a dove-tail slot for the reception of a similarly formed cutting blade. One wall of the slot is also inclined toward the wall opposite thereby forming an opening 35 tapered in transverse directions. A tapered wedge, having an interlocking engagement with the blade, fits snugly between the blade and the wall of the slot and when assembled and driven in place securely locks the blade against movement.

To increase the frictional resistance to wedge movement and to provide a positive means for 45 making fine adjustments of the cutter blades, one face of the wedge member is provided with a plurality of V-shaped serrations, extending in the direction of its taper, and which are adapted to interfit with cooperating serrations formed in the adjacent wall of the cutter body. For example, the cutter tooth and wedge may be 50 moved from its socket and reinserted set over from its former position a distance equal to the width of the number of serrations intervening, and thus, because of the mutual inclination of the intersecting planes of the two side walls, the position of the blade is caused to be changed both

radially and axially. A further distinguishing feature of this invention is in the placing of the serrations upon the wedge member. The main advantage gained being that the wedges, although made of a good grade of steel, are more easily machined than metal such as stellite, tungsten-carbide or other hardened and ground high speed steel which usually go into the construction of the blades.

Ordinarily, the off-setting of each blade one 60 serration gives more than enough material for the resharpening and resizing of the cutter consequently too much blade stock is needlessly removed and the life of the blades thereby materially shortened. In combination with the compound taper blade lock hereinbefore mentioned this invention contemplates a means for reducing the amount of material to be removed in regrinding in order to conserve the stock and thus prolong the life of the individual blades. With this 65 end in view each series of serrations formed in the successive slots in the cutter body are staggered, with respect to a preceding series, a fraction of the increment between two serrations so that the blades may be successively advanced 70 one or more slots around the tool and in this way move each blade outwardly from the cutter an amount sufficient for accurate regrinding to size without incurring undue waste of material.

This invention further contemplates a provision for adjusting the blade outwardly in one direction only in order to effect major changes in the width of the slot to be cut, if the invention is applied to a slotting tool, or to effect major adjustments in the diameter of the cutter, if the 80 invention be applied to a tool of the face mill type. For this purpose one of the members, either blade or wedge, is provided with one or more projections which are adapted to interfit with and engage complementary cavities formed in the other member and by adjusting one member relative to the other, the blade will, when re-inserted, project more or less from the holder according to the increment between, or the spacing or arrangement of, the interlocking devices.

A positive interlock between wedge and blade 95 has the further advantage of preventing relative movement between the two members and thereby prevents the blade from shifting its position under load. The wedge member being tapered in 105 the direction of the end thrusts upon the tool and being interlocked with the blade has a tendency to move further inwardly and thus impinge upon the blade member more firmly to hold it in its seat.

Other objects and advantages will be in part indicated in the following description and in part rendered apparent therefrom in connection with the annexed drawings.

5 To enable others skilled in the art so fully to apprehend the underlying features hereof that they may embody the same in the various ways contemplated by this invention, drawings depicting a preferred typical construction have been 10 annexed as a part of this disclosure and, in such drawings, like characters of reference denote corresponding parts throughout all the views, of which:-

Figures 1 and 2 represent end and side views 15 respectively of a face mill embodying this invention. Figs. 3, 4 and 5 are top, side and end views of a cutter detached from the holder. Figs. 6, 7 and 8 represent top, side and end views of the wedge member, likewise detached from the 20 holder. Fig. 9 is an enlarged portion of a cutter more clearly illustrating the manner of effecting radial adjustment of the blades in a circular tool. Fig. 10 is a side view thereof illustrating the effect 25 of a radial adjustment upon the axial position of the blade. Fig. 11 is a sectional view illustrating one form of blade and wedge interlock and the effect of moving the blade with respect to the wedge one or more positions to effect a major 30 adjustment or to compensate for numerous re-grindings. Fig. 12 is an end view of Fig. 11. Figs. 13 and 14 represent an adaptation of this 35 invention to single point tools, such as lathe, planer or shaper tools, fly cutter, etc., but it will be understood, however, that its use in broaches, gang tools, etc., is also contemplated.

Referring more particularly to Figs. 1 and 2, the invention is shown therein as applied to a face mill comprising a base or body member 1 formed of a metal having the necessary characteristics 40 for tools of this character and which obviously need not be of such high grade of steel as that of the blade. About the periphery of the body 1 a number of double tapered slots 2 are provided for the reception of the blades 3 and wedges 45 which together form units complementally tapered.

Details of a representative blade and wedge are depicted in Figs. 3 to 8 inclusive, and in this particular type of cutter the blade is tapered radially, the side *a* being inclined with respect to the side *b* approximately an angle of 2°, the wider portion of the blade forming the base or part 50 nearest the axis of the cutter. Along its major axis, the faces *a* and *b* of the blade are parallel as illustrated in Fig. 3.

The wedge member 4 is tapered transversely to the blade, that is, surfaces *a* and *d* are arranged parallel to each other (radially with respect to the axis of the cutter) but tapered in a direction 60 substantially paralleling the cutter axis, as shown by Fig. 6. The angle of taper need only be great enough to impinge the blade tightly against the adjacent wall *e* of the slot in the holder but not so great as to work loose under the vibrating effects 65 of a tooling operation. As herein shown the angle of taper on the wedge approximates 5°, which has been found to be highly satisfactory, permitting easy assembling and disassembling as well as to securely hold the blade in place while 70 under load.

It will be observed that the radial thrusts acting upon the blade tend to move the same inwardly (toward the center). Movement in this direction, however, is prevented by means of an 75 overhanging portion or ledge 5 provided by the

wedge member which forms an abutment or base upon which the blade seats. Radial movement of the blade outwardly is also prevented by reason of the dove-tailed formation of the blade and slot.

So that the wedge member does not move radially in either direction, a series of serrations 6 extending in the general direction of the taper are formed upon the wedge and which are adapted to interfit with a similar series of serrations 7 formed on the side wall of the slot in the holder. Thus, the blade is held positively against radial movement and the radial forces acting thereupon are transmitted first to the wedge thence to the cutter body. 80

Axial movement of the blades with respect to the holder is largely if not entirely prevented because of the impinging effect of the wedge member and the friction between surfaces *a*—*e* and *c*—*b*; however, as an additional measure, means are provided for positively locking the wedge and blade against relative movement. The detail Figs. 4 and 7 illustrate one such form of lock which comprises a pin or abutment 8 carried preferably by the wedge member and one or more complementally formed grooves 9 formed in the other member. When the blade and wedge are placed with their faces *b* and *c* together, the pin 8 engages one of the grooves 9 and prevents the parts from moving axially relatively to each other. 90

The two part double tapered unit thus formed is then inserted in the slot in the holder and tapped gently in place. The assembled cutter is next ground to size and is ready for operation. 100

After a period of usage the blades will become dulled and must be resharpened if accuracy and good work are to be maintained. Figs. 9 and 12 illustrate how fine adjustments of the blades can be made without sacrificing any of the strength of the cutter nor incurring undue waste of material. The compounded unit 3—4 is removed from the holder and set-over one or more serrations radially and again reinserted. The stepping over of the compoundly tapered unit toward the converging walls of the slot, increases the 110 diameter of the cutter as well as its length or width as the case may be, for the reason that the slot being smaller the blade and wedge will not enter the holder as great a distance. Consequently, the component of the double tapers 115 effects an axial repositioning of the blade sufficient to allow for regrinding and truing to size. 120

Extremely fine adjustments of the blades may also be effected if each series of serrations 7 is cut in the holder slightly off-set from a succeeding series by an amount equal to a fraction of the increment between two serrations, and then successively advancing the compounded units one or more slots. In this way each unit projects only a fraction of the increment between 135 two serrations and exceptionally close adjustments in size may be made. Fig. 9 represents a portion of a rotary cutter in which for the purpose of illustration depicts a series of blades stepped out unequal distances better to illustrate the ease 140 at which radial adjustments may be made. Fig. 10 is a projection of Fig. 9, showing how radial adjustment of the blades effects also an axial adjustment thereof. The staggering or off-setting of the serrations in the cutter body for attaining fine adjustment radially, likewise effects finer adjustments axially when the blades are successively advanced. 145

A further refinement of this invention lies in the fact that adjustments of the blades in one di- 150

rection may be made without disturbing the transverse adjustment. Fig. 11 illustrates clearly how this may be accomplished, and in which the dotted line position of the blade represents its original size and the full line position the size after a number of regrinding operations have been performed thereon and the blade moved outwardly one or more of the notches 9. The blade per se, not being tapered in this direction (axially of the cutter) permits of such an adjustment relative to the wedge 4 without changing its position radially. Owing to its comparative inexpensiveness the blade and wedge are formed preferably with the pin and slot connection as shown but it will be understood, however, that other forms of interlocking arrangements are contemplated. For example, the lower edge of the blade and the engaging face 5 of the abutment may readily be provided with complementary and interfitting serrations whereby finer adjustments of the blades in one direction may be easily effected in the same manner as previously explained.

Obviously, this form of inserted blade and lock 25 is adaptable to other types of tools such as left and right handed or faced cutting tools, single or multi-point. Figs. 13 and 14 illustrate its application to a single point tool and in which the holder is represented as 10 and provides a double tapered slot 12 similar in all respects to the slots formed in the rotary cutter previously described. One wall of the slot 12, preferably the upper wall, or the wall opposite the one that receives the downward thrusts occurring during 30 tooling operations, is provided with serrations 12^a which interfit the serrations 13 formed on the wedge 14. The wedge 14 and blade 16 are transversely tapered, as hereinbefore explained, and when placed and keyed together form a composite unit having compound tapers commensurate 35 with the tapers of the slot formed in the holder.

The terms "compoundly tapered" opening, an opening having "compoundly inclined" side walls, a "double tapered" opening, "transversely tapered" as herein used are intended to mean an opening or a member, at least two of the side walls of which are inclined with respect to each other, or are tapered in two or more directions. In the case of a rotary cutter, for example, the 40 tapers of the blade opening would ordinarily extend radially and axially of the cutter body, while in the case of a single point tool, such as a lathe tool, the tapers of the blade opening would ordinarily extend in the direction of the general axis of the holder and, also, in a direction perpendicular thereto. In either of the above 45 examples it will be seen, that the two tapers extending in transverse directions afford a "compoundly tapered" opening.

Without further analysis, the foregoing will so 50 fully reveal the gist of this invention that others can, by applying current knowledge, readily adapt it for various utilizations by retaining one or more of the features that, from the standpoint of the prior art, fairly constitute essential 55 characteristics of either the generic or specific aspects of this invention and, therefore, such adaptations should be, and are intended to be, comprehended within the meaning and range of 60 equivalency of the following claims:—

Having thus revealed this invention, I claim as 65 new and desire to secure the following combinations and elements, or equivalents thereof, by Letters Patent of United States:—

70 1. An inserted blade metal cutting tool com-

bining, a holder member provided with an opening having two of its side walls transversely inclined with respect to each other so that a compoundly tapered opening is provided; a composite unit adapted to be pre-assembled and inserted within said opening, said unit comprising a tapered blade member and a tapered wedge member, the tapers on said members extending in transverse directions; and means including a ledge portion provided by said wedge member adapted to provide a seat for said blade for locking said members together when the unit is inserted in said holder.

2. An inserted blade metal cutting tool combining, a holder member provided with an aperture having compoundly inclined side walls; a composite unit adapted to be pre-assembled and inserted within said opening, said unit comprising a tapered blade member and a tapered wedge member, the tapers on said members extending in transverse planes; and interlocking means comprising a ledge portion provided by said wedge and a pin and slot connection between said blade and wedge for maintaining said members in predetermined relation to each other when the composite unit is inserted in said aperture.

3. An inserted blade tool combining a holder member provided with an aperture having compoundly inclined side walls; a blade member insertable in said opening and having one wall thereof inclined at an angle corresponding to the angle of inclination of one of the walls of said aperture; a locking member insertable within said aperture adjacent said blade and having one side thereof inclined at an angle corresponding to the angle of inclination of the adjacent wall of said aperture; and interlocking means between contacting portions of said blade and wedge adapted positively to lock said members against relative movement in transverse directions.

4. An inserted blade tool combining a holder member having a double tapered opening formed therein; a blade member insertable in said opening and having one wall thereof inclined at an angle corresponding to the angle of inclination of one of the walls of said opening; a locking member insertable within said opening adjacent said blade and having one side thereof inclined at an angle corresponding to the angle of inclination of the other inclined wall of said aperture; and an adjustable connection between said blade and said locking member for locking said members against relative movement in transverse directions.

5. A composite cutter blade for metal working tools adapted to be removably mounted in a compoundly tapered opening formed in a suitable holder comprising a tapered blade member and a tapered locking member, the taper on said locking member extending in a direction perpendicular to the direction of taper on said blade; and means maintaining the two members in a predetermined position relative to each other comprising a blade seat formed upon the locking member and a blade locating stud formed on said seat, said stud being adapted to engage a recess in the said blade and to cooperate with said seat to prevent relative movement between the two members.

6. A rotary metal cutting tool combining, a holder member provided with a dove-tail opening tapered in the general direction of the axis of rotation of said holder member; a tapered blade member insertable in said opening; lock-

ing means therefor, said means comprising a wedge shaped member the taper of which extends in a direction perpendicular to the direction of the taper formed on said blade; and interengaging means between said blade and wedge members comprising a blade seat formed upon the wedge member and a pin and recess connection between adjacent face portions of said blade and wedge adapted when engaged to positively 10 maintain the blade in an adjusted position radially and axially of said holder member.

7. An inserted blade metal cutting tool combining, a holder member provided with a compoundly tapered opening; a composite unit insertable within said opening, said unit comprising a tapered blade member and a tapered wedge member, the tapers on said members extending in transverse directions; a blade seat formed on said wedge member; and interlocking means between said blade and said seat portion for maintaining said blade member in adjusted position.

8. A cutter tool of the inserted blade type

combining a holder member provided with a compoundly tapered opening; a tapered composite unit insertable in said opening, said unit comprising a blade member and a locking member, which together form a unit tapered in conformity with the compoundly tapered opening; means for adjusting said blade member with respect to said holder in two directions, comprising a series of serrations formed upon the wall of said locking member and the adjacent wall of the opening in the holder and an abutment element provided by one of the members of said composite unit adapted to engage the other member of said unit for maintaining said members in a predetermined position in said holder.

9. A cutter tool according to the preceding claim characterized by the provision of interengaging means between the members of said composite unit for positively locking said members against lateral movement relative to each other.
